UNITED STATES PATENT OFFICE.

RAYMOND W. TIBBETTS, OF BOSTON, MASSACHUSETTS, AND MYRON S. CURTIS, OF PAWTUCKET, RHODE ISLAND.

REFRIGERATING APPARATUS.

Application filed December 8, 1919, Serial No. 343,306. Renewed September 8, 1925.

To all whom it may concern:

Be it known that we, RAYMOND W. TIBBETTS, of Boston, Massachusetts, and MYRON S. CURTIS, of Pawtucket, Rhode Island, have 5 invented certain new and useful Improvements in Refrigerating Apparatus; and do hereby declare that the following is a full, clear, and exact description thereof.

Our invention relates to refrigerating apparatus in which a gas is alternately condensed and expanded, and the object is to provide apparatus of simple and compact construction, economical in its consumption of power to run it, and withal, capable of 15 producing a satisfactory low temperature.

In the drawings is illustrated one embodiment of our invention, in which drawings:

Fig. 1, is a vertical section of such apparatus;

Fig. 2 is a view in section of a desirable form of rotary pump that we may use.

Briefly described, our invention employs a pump by which the gaseous refrigerant, 25 returning from the expansion chamber is compressed and delivered into a condensing chamber to liquefy it, and we place the pump within the condensing chamber, and, by preference, submerge it in the pump lubricating and sealing oil.

Since our invention, in its general embodiment, has, as a matter of convenient design, conformed with what is customary in the art (the differences therefrom being 35 pointed out in the claims) our apparatus includes an expansion chamber 10 in which the refrigerant gas expands to produce the cooling effect; a pump 11, to whose intake 390 gas passes from a passage 12 (see Fig.

40 1) which by a connection that includes pipe, 13 is in communication with the expansion chamber for conveying the expanded gas therefrom; a condensing chamber 14 into which the gas is delivered from the pump;

45 and a pipe coil 15 within the condensing chamber, through which a cooling medium, such as water, is circulated to effect the condensation of the gas, said condensing chamber 14 having an outlet 16 in its bottom 50 from which a pipe 17 runs to the expansion chamber to convey the condensed refrigerant gas thereto.

We place the pump 11 within the condensing chamber, and it is conveniently 55 mounted on the detachable end wall 18 of

said chamber; which, on the outside, has a stuffing box 19 through which the pump shaft 20 extends to an external motor (not shown). Contiguous to the pump, a vertical partition 21 rises from the bottom of the chamber 14, to substantially mid-height thereof, thus producing within the chamber an oil well or sump into which the pump outlet 22 delivers the mingled gas and oil. Oil enters the pump through an inlet 23 leading from said sump into the pump, the pump being preferably submerged in the oil in the sump.

Interposed within, or forming part of the pipe connection between expansion chamber 70 and pump, is a passage, or chamber 24 in a box or fitting 25, which at one end has a screw connection with the pipe 13 and at the other end has a screw connection with the pump intake 12, and within said 75 chamber is a check valve 26 that opens towards the pump. At a point between the check valve and pump intake, the chamber contains a diaphragm 28, exposed on one side to or influenced by the pressure within the 80 chamber 24. On its opposite side the diaphragm carries a valve 29, which, when the diaphragm is released, uncovers a seat 30, in a passage 31 to which the inlet pipe from a source of water is connected and from the 85 same side of the diaphragm as that having the valve, a port or passage 32 leads, to which is connected the pipe 33 to the inlet end of the cooling coil 15 having an outlet, 150. When the pump is running, the 90 consequent reduction of pressure in the chamber 24 keeps the check valve 26 open and there is a continuous flow of the gas to the pump, and the pressure on the diaphragm is not enough to seat its valve 29, 95 so that there is, at the same time, a continuous flow of cooling liquid through the coil 15. When the pump is not running, the gas pressure in the chamber 24 seats the check valve 26, to prevent back flow 100 of gas, and moves the diaphragm to seat its valve 29, and cut off the flow of cooling liquid. Thus, automatically according to whether the pump runs or stops, the flow of cooling liquid is permitted, or cut off, and, 105 hence, such liquid is supplied only when the apparatus is in operation.

The pump may be water-jacketed or not, and be of any desired construction, and if of rotary type, it may have the construction 110

shown in the drawings, Figs. 1 and 2, it comprising intermeshing gears 34 and 35, the gear 34 being on the shaft 20, and a casting 36, with a water-jacket 37, around the 5 gears, and a chamber 38 around the water jacket, that forms an oil reservoir, from which oppositely situated ducts 39 and 40 lead to the gear chamber. In the path of oil and gas leaving the duct 40, is a baffle 10 wall or plate 41 that curves downward at opposite ends which causes the oil to flow downward to the reservoir bottom, while the gas, passing around the baffle, emerges from the pump through its eduction port 15 and enters the condensing chamber. Oil is admitted to the gears by the port 39, so proportioned as to supply only sufficient for lubrication and sealing, and gas is drawn by the pump through the port 390.

20 The location of the pump and the oil and gas separating means within the condensing chamber, makes a simple and compact structure. It also has the important advantage that while most of the gas liquefied by 25 contact with the cooling coil falls to the bottom of the chamber, outside the oil well, or sump, some will fall on the pump, or on the oil. If the pump and oil are warm enough, (and their temperature is raised by the running 30 of the apparatus) the refrigerant will at once return to its gaseous state, and thus cool pump or oil. Should the refrigerant remain liquid, it will be drawn along with the oil into the pump, and as the interior of 35 the latter will always be warm enough to evaporate the liquid refrigerant, the latter within the pump will become a gas and exert a cooling effect on pump and oil.

40 A needle valve, 41, controls the flow of the condensed gas through pipe, 17, into the expansion chamber.

Of course, we do not restrict ourselves only to such an embodiment of our invention as we have shown and described herein, as not that embodiment, but the scope of 45 the claims is the measure of our protection.

We claim:—

1. A gas using refrigerating apparatus having a condensing chamber with two compartments side by side and in communication in the upper part of the chamber, one of such compartments being an oil well, a pump within said chamber having an outlet 50 for mingled oil and gas with its discharge end located to deliver mingled oil and gas to 55

the oil well and a passage being provided leading into the pump from such oil well whereby the well contents enter the pump, and gas condensing surfaces in the upper part of the condensing chamber above both 60 compartments therein.

2. A gas using refrigerating apparatus having a condensing chamber, a vertical partition reaching part way to the top of the chamber and sub-dividing the chamber into 65 two compartments one of such compartments being an oil well, a pump within such chamber, an opening being provided from the oil well into the pump, an outlet from the pump for oil and refrigerant taken into 70 the pump, said outlet having its discharge end located to direct mingled oil and refrigerant into said oil well, and a condensing coil within the chamber with portions in each of said compartments.

3. The combination of a chamber into which a refrigerant gas to be condensed is introduced, means for the flow of a condensing liquid associated with such chamber, a pump, means for the flow from such condensing chamber to the pump of the refrigerant comprising a chamber, a diaphragm within such chamber providing a passage through the chamber of refrigerant on its way to the pump and also providing a passage for the condensing liquid, and a valve carried by said diaphragm to control the flow of said condensing liquid.

4. A gas using refrigerating apparatus having a chamber, a partition separating such chamber into two adjoining compartments one of such compartments constituting a lubricant well, said compartments being in communication, a pump within such chamber having an outlet for mingled lubricant and refrigerant with its discharge end located to deliver mingled lubricant and refrigerant into the chamber and the pump being in communication with said well to receive the contents thereof, means to condense gas discharged from said outlet into the condensing chamber so arranged that a portion of the condensed gas will be delivered to said well and means to deliver the remaining portion of the condensed gas to 105 the exterior of said condensing chamber.

In testimony that we claim the foregoing, we have hereunto set our hands.

RAYMOND W. TIBBETTS.
MYRON S. CURTIS.
